UNITED STATES PATENT OFFICE.

WILLIAM E. SCOFIELD, OF LONG ISLAND CITY, NEW YORK, ASSIGNOR TO THE SUNLIGHT GAS MACHINE COMPANY, OF NEW YORK, N. Y., A CORPORATION OF NEW JERSEY.

ACETYLENE-GAS GENERATOR.

SPECIFICATION forming part of Letters Patent No. 720,976, dated February 17, 1903.

Application filed December 28, 1901. Serial No. 88,439. (No model.)

To all whom it may concern:

Be it known that I, WILLIAM E. SCOFIELD, a citizen of the United States, residing at Long Island City, borough of Queens, county of 5 Queens, and State of New York, have made a new and useful Invention in Acetylene-Gas Generators, of which the following is a specification.

My invention is directed particularly to 10 improvements upon an acetylene-gas generator disclosed in a prior patent, No. 657,364, granted to me by the United States Patent Office on the 4th day of September, 1900; and it has for its objects, first, to simplify the 15 structural apparatus of the generator disclosed in the before-mentioned patent with relation to the means for suspending the carbid-containing cartridges within the gas-generating chamber and withdrawing them there- 20 from; second, to provide improved means for locking the suspended cartridges within the upper part of the generator in such manner that they can only be released by the releasing mechanism when actuated; third, to pro- 25 vide a novel form of carbid-containing cartridge weighted at its lower end and so constructed that it will always assume a vertical position when released and allowed to descend through the water into the gas-gener- 30 ating chamber, said cartridge having also a further novel feature in the nature of a removable carbid-containing cup perforated at its bottom; fourth, to provide means for more effectually releasing the carbid-containing 35 cartridges in succession as the bell of the gasometer descends and also to provide means for compensating for any lost motion in said re- 40 leasing means, so that the carbid-containing cartridges will be surely released in sequence as the bell of the gasometer descends to its lowest position after the volume of gas previously generated has been consumed.

Referring now to the drawings, Figure 1 is a side elevational view of the entire apparatus, illustrating also a gasometer connected thereto, one of the carbid-containing cartridges and its flexible supporting-chain being shown, respectively, in dotted lines in its locked and submerged positions. Fig. 2 is 45 an enlarged detail side elevational view of

the mechanism which supports and releases the carbid-cartridges and the compensating mechanism for taking up any lost motion thereof, the driving-shaft therefor being shown in section and as seen looking at Fig. 55 3 in the direction of the arrows. Fig. 3 is a plan view illustrating the carbid-cartridges in their supported positions with their caps or covers removed, showing the carbid, together with the releasing mechanism and its 60 operative connection with the bell of the gasometer, the pipe between the gasometer and the gas-generating chamber and the blow-off pipes being also shown. Fig. 4 is a part side elevational part sectional view taken through 65 that part of the apparatus shown in Fig. 1 which regulates the blow-off of the gas from the gas-generating chamber, the withdrawal of the water from the same, and the connections between the gas-generating chamber 70 and the gasometer, the same being viewed in the direction of the arrows from the left toward the right hand side of the drawings. Fig. 5 is an enlarged part elevational part sectional view of one of the carbid-containing 75 cartridges, illustrating also its supporting bail and chain. Fig. 6 is an enlarged plan view of the bottom of the interior carbid-containing cup. Fig. 7 is an enlarged plan view as seen looking at Fig. 5 from the top toward 80 the bottom of the drawings, the supporting-bail, however, not being shown in this view.

Referring now to the drawings in detail, 1 represents the gas-generating chamber, 2 the gasometer, and 3 the common supporting- 85 base.

4 is the door at the upper end of the gas-generating chamber for receiving and removing the carbid-containing cartridges, and 5 is an outlet for a two-way cock at the bottom 90 of the gas-generating chamber for withdrawing the water therefrom when desired.

6 is a vertical wall adapted to suspend the carbid-containing cartridges in their vertical position. 95

7 is a curved side or surface adapted to convey the carbid-containing cartridges to their suspended positions when released.

8 is a metallic frame adapted to support certain parts of the apparatus and to connect 100

the upper end of the gas-generating chamber mechanically with the gasometer.

10 is a seal or apron extending downward into the water and constituting one of the 5 interior walls of the gas-generating and gas-containing chamber.

11 11 11 are hooks secured to the inner face of the frame 8 and adapted to receive rings 9 9 9 at the outer ends of chains or other flexible supports 29 29, &c., the other ends of which are secured directly to bails 28 of the carbid-containing cartridges 22.

13 is a driving-shaft journaled at its opposite ends in brackets 12 12 and provided at 15 intervals with releasing-fingers 15 15, radially disposed, said releasing-fingers being secured to the shaft by set-screws, as shown in Fig. 3.

16 16 16 are barrels for supporting sliding 20 locking-bolts 18 18 18.

19 19 are trunnions passing through the bolts and adapted to move in slots in the lower ends of releasing-levers 20, supported by pivot-pins 21 21 on the barrels 16 16.

25 14 is a ratchet-wheel supported by the shaft 13, and 43 is a locking detent or pawl therefor.

47' is an arm hinged to a curved arm 42, carried at the top of the bell of the gasometer and adapted in its downward movement to 30 operate the releasing mechanism.

The details of construction of this locking and releasing mechanism as described so far are not essentially different from the like parts disclosed in the before-mentioned patent, except that in the present case the ratchet-wheel 14 is provided with an indefinite number of teeth, while in the before-mentioned patent the ratchet-wheel has eight teeth, or as many teeth as there are carbid-cartridges, 35 40 the arm corresponding to the arm 47' in that case acting directly on one tooth of the ratchet-wheel at each descent. With such an arrangement, however, there was not always such a certainty of operation as might be desired, owing to the fact that the lower end 45 of the arm might not always reach the pawl of the ratchet-wheel at the proper position to release the locked cartridge. It therefore became necessary to devise means whereby each 50 descent of the bell would surely release the proper carbid-cartridge and also to provide compensating means for assuring the fact that the releasing-fingers 15 would always assume a definite position with relation to the releasing-levers 20, so that the apparatus would 55 work with the greatest nicety. This is accomplished through the agency of two sets of means: first, a pivoted lever 17, carried by the shaft 13 and having at its upper end a pivoted 60 pawl 25 and at its lower end a pivoted weight 30, adapted to return the pawl to its upper position when released, this position being always assured by reason of the pivoted lever 17 coming into contact with the stop-pin 27 in the bracket 12 when the weight 30 returns said lever to its lowest position; second, compensating means consisting of a lever 34, pivoted

directly to the body of the gas-generating chamber and having at its free end a weight 37, 33 being a roller adapted to roll freely 70 over the teeth of a compensating star-wheel 31, carried by the shaft 13, the relations of the weight 37, the roller 33, and star-wheel 31 being such that when said roller passes one of the points of the star-wheel it will 75 always advance the next succeeding operating-finger 15 just into mechanical contact with its releasing-lever 20, as will be more particularly described later on in connection with the description of the mode of opera- 80 tion.

44 44 are locking-arms located one above each bolt 18 and adapted to hold the carbid-containing cartridge in its locked position, so that said cartridge cannot be removed after 85 it is once put in place otherwise than through the action of the mechanism itself.

Referring now to Figs. 5, 6, and 7 of the drawings for a detailed description of the carbid-containing cartridges, 22 represents the 90 outer shell of the cartridge, provided with ears for receiving the bail 28, and 32 is a locking-lug on one face thereof for receiving the end of the locking-bolt 18. 23 is a cone-shaped metallic base having a perforation or opening, as shown, for permitting the water to enter the cartridge from the bottom, said base being of sufficient weight to assure the fact that the cartridge when released will descend by its own weight to the lowest possible position and right itself beneath the water in the position shown in Fig. 1 with the flexible supporting-chain 29 under tension. 39 is an inner carbid-containing cup having a perforated bottom 24 (see Fig. 6) and a bayonet- 105 joint for removably securing it within the outer shell of the cartridge 22, and 26 is a puppet-valve for permitting the gas when generated within the cartridge to escape, said valve being seated in the removable cap 45 110 in the same manner as the like valve is seated in the removable cap of the cartridge disclosed in my before-mentioned patent.

Referring now to Figs. 1 and 4, I will describe that portion of the improvement directed to the means for connecting the gas-generating chamber to and disconnecting it from the gasometer and at the same time closing the cock for withdrawing the water from the gas-generating chamber and the blow-off pipe for preventing the gas from escaping into the open air from said chamber, and vice versa. 5 represents the water-cock outlet at the bottom of the gas-chamber, and 36 a pipe connecting the gas-generating chamber with the gasometer. 47 is a blow-off pipe for the gas-generating chamber, and 51 the connection with the three-way cock for making the connections at will. 50' is a two-way cock for permitting of the withdrawal of the 120 water from the generating-chamber or not, as desired. 49 49 are wrenches adapted to engage the cocks 50 and 50', and 46 is a connecting-joint for said wrenches, 48 being an 125 130

operating-handle secured to a point easily accessible to an attendant. 48' is a blow-off pipe for the outer portion of the gas-generating chamber in the event of any gas escaping to that part thereof.

I will now describe the mode of operation. The powdered carbid is first placed in the inner cups 39 and they are placed in the carbid-containing cartridges 22, after which the caps or covers are secured in place. The rings 9 are then hung upon the hooks 11 and the several carbid-containing cartridges are hung upon the bolts 18 by first pressing each bolt inward through the agency of the ear or lug 32 and then lifting the cartridge and the ear or lug carried thereby upward, so that the bolt snaps into position in the grooved part of said ear, (see Fig. 5,) and the ear or lug is locked against removal by the locking-arm 44. (See Figs. 1 and 2.) Upon the supposition, now, that the third finger 15 is in the position shown in Fig. 3 and that gas is being consumed from the gasometer, the bell 41 will descend until the arm 47' comes into mechanical contact with the curved pawl 25, causing it to descend and carry with it the pivoted arm 17 and at the same time lifting the weight 30 until the finger 15 causes the bolt 18 to be withdrawn, thus releasing the cartridge and allowing it to descend by its own weight into the position shown in Fig. 1, where it is held by the supporting-chain 29, so that the gas now being generated by the water escapes upward into the gas-generating chamber. Consequently gas passes from the gas-generating chamber by the pipe 36 to the gasometer 2, upon the supposition, of course, that the three-way cock 50 is in such position as to connect the two chambers, in which event the cock 50' at the bottom of the gas-generating chamber is closed. As the gas is generated, therefore, the bell 41 rises, and with it the arm 47', the pawl 25, and pivoted lever 17, the latter under the influence of the weight 30. All the points of the star-wheel 31 have, respectively, such a relation to the several releasing-fingers 15 that after the cartridge is released the roller 33, acting under the influence of the weight 37, will advance the shaft 13, and hence the fingers carried thereby, always to the proper position to bring the next succeeding finger in the series in connection with its releasing-lever 20, thereby avoiding any possibility of an error of operation in the apparatus due to lost motion. This feature constitutes an essential element of my invention in that it renders the apparatus automatic and certain in its operation as to the successive release of the cartridges when the gasometer descends after the corresponding volumes of gas have been consumed.

It will be apparent that by substituting a flexible means of suspension for the cartridges and by weighting the lower end thereof sufficiently I have materially improved the invention disclosed in my prior patent in that I

avoid the necessity of any guiding means for guiding the cartridges in their descent. I also avoid any possibility of the cartridges becoming checked or suspended at points midway in their descent, making it absolutely certain that said cartridges will always assume the proper position—namely, vertical—so that the gas will be generated and ascend into the receiving-chamber. Such a flexible means of support as the chain 29 also makes it possible to withdraw the cartridges with a minimum amount of annoyance or trouble, after which the inner carbid-containing cup 39 may be removed, the contents emptied, and then be refilled without necessitating the conveyance of the entire cartridge to a distant point to be filled, and these inner cups may, if preferred, be provided with perforated covers. By the agency of the locking mechanism, whereby the cartridges are locked in their suspended positions, no one can tamper with or release them other than by rotating the proper releasing mechanism, a feature of importance in that it assures the operation of the apparatus in the manner it is intended it should operate. The compensating mechanism in the nature of the star-wheel and weighted lever, with its operating-lever 33, also assures an accuracy of operation which was not attainable with the apparatus disclosed in my before-mentioned patent.

I believe it is broadly new with me to construct and suspend directly from the frame of the carbid-generator a carbid-containing cartridge by means of a flexible support that when released it will assume its proper position without guiding means and that it may be withdrawn at will after the gas has been generated, and my claims are generic as to this feature of improvement. I believe it is also broadly new with me to construct a carbid-cartridge of two parts, one of which is provided with a perforated metallic base and constitutes the cartridge proper and the other the containing cell or vessel for the carbid, said parts being removable or detachable the one from the other.

Having thus described my invention, what I claim, and desire to secure by Letters Patent of the United States, is—

1. An acetylene - gas generator having a gas-generating chamber and a supporting-frame; in combination with a carbid-containing cartridge provided with a flexible means of support secured at one end to the supporting-frame and at the other to the cartridge and adapted to sustain it within the chamber, said cartridge being provided with sufficient weight at its lower end to maintain it in a vertical submerged position, substantially as described.

2. An acetylene - gas generator having a gas-generating chamber, a supporting-frame and one or more carbid-containing cartridges; in combination with means for supporting the same above the water; together with a

flexible means of support attached directly to the frame and to each cartridge and adapted to sustain the cartridge, when released, in a submerged position within the generating-
5 chamber, said cartridge being weighted at its lower end to such an extent as to maintain it always in a vertical position, substantially as described.

3. An acetylene-gas generator having a
10 gas-generating chamber, a supporting-frame and one or more carbid-containing cartridges; in combination with means for supporting the same above the water; together with a flexible means of support attached directly to
15 the frame and to each cartridge and adapted to sustain the cartridge, when released, in a submerged position, and automatic releasing mechanism therefor, said cartridge being weighted at its lower end to such an extent
20 as to maintain it always in a vertical position, substantially as described.

4. An acetylene-gas generator having a gas-generating chamber and a series of carbid-containing cartridges; in combination
25 with locking mechanism for supporting said cartridges above the water in the generating-chamber; together with automatic releasing mechanism actuated by the descent of the gasometer-bell, and compensating mechanism
30 for bringing the releasing mechanism always into operative relation with the locking mechanism so that the cartridges will be successively released as gas is consumed, substantially as described.

35 5. In an acetylene-gas generator mechanism for supporting the carbid-containing cartridges above the water in the gas-generating chamber; consisting of a series of locking-bolts; in combination with releasing mechanism adapted to withdraw or release said bolts
40

in sequence; together with compensating mechanism adapted to bring the releasing mechanism always into operative relation with the locking mechanism in sequence after each cartridge is released, substantially 45 as described.

6. A carbid-containing cartridge for an acetylene-gas generator consisting of two parts, in the nature of an outer shell and an inner containing cell or vessel detachable
50 therefrom, said outer shell being provided with a perforated metallic base, substantially as described.

7. A carbid-containing cartridge for an acetylene-gas generator provided with flexible means of support for sustaining it in a submerged position within the gas-generating chamber, said cartridge being weighted at its lower end, substantially as described.
55

8. A carbid-containing cartridge for an acetylene-gas generator, consisting of an outer shell provided with a perforated weighted bottom, a removable cap, a bail, and a flexible support; in combination with a removable inner cup perforated at its bottom,
60 65 substantially as described.

9. A carbid-containing cartridge for an acetylene-gas generator, consisting of an outer shell provided with a perforated weighted bottom; a removable cap having a puppet-valve; a bail and a flexible support; in combination with a removable inner cup perforated at its bottom,
70 substantially as described.

In testimony whereof I have signed my name to this specification in the presence of
75 two subscribing witnesses.

WILLIAM E. SCOFIELD.
